(57) **CLAIM**

The ornamental design for a bib, as shown and described.

DESCRIPTION

FIG. 1 is a perspective top front right view of a bib, showing my new design;

FIG. 2 is a perspective top rear left view thereof;

FIG. 3 is a front elevation view thereof;

FIG. 4 is a rear elevation view thereof;

FIG. 5 is a top plan view thereof; and,

FIG. 6 is a right elevation view.

The dashed lines represent perforations on the bib and are part of the claimed design.

1 Claim, 5 Drawing Sheets
